UNITED STATES PATENT OFFICE.

JOSEPH D. ADAMS AND ROY E. ADAMS, OF INDIANAPOLIS, INDIANA; SAID ROY E. ADAMS ASSIGNOR TO SAID JOSEPH D. ADAMS.

ROAD-DRAG.

968,912.

Specification of Letters Patent. Patented Aug. 30, 1910.

Application filed November 15, 1909. Serial No. 528,234.

To all whom it may concern:

Be it known that we, JOSEPH D. ADAMS and ROY E. ADAMS, citizens of the United States, residing at Indianapolis, in the 5 county of Marion and State of Indiana, have invented certain new and useful Improvements in Road-Drags, of which the following is a specification.

The object of our invention is to produce 10 a cheaply manufactured yet very rigid and economical road drag by means of which roads may be quickly reshaped.

The accompanying drawings illustrate our invention.

15 Figure 1 is a perspective from the rear of the machine, and Fig. 2 a plan.

In the drawings, 10 and 11 indicate two 20 diagonally arranged forward drags, which, except that one is right and the other left, 25 are identical. Arranged to the rear of the drags 10 and 11 is a rear drag 12.

The drags 10 and 11 each comprise a pair 25 of upper frame bars 13, 13 preferably formed of angle irons arranged to have two vertical legs and two horizontal legs projected toward each other. Secured to the upper faces of the two horizontal legs of bars 13, 13 is a bar or board 13'. Arranged transversely below the bars 13, 13, one in 30 front of the other, are two angle-iron bars 14, 14 having rearwardly projecting substantially horizontal legs and substantially downwardly projecting vertical legs. Secured to the horizontal leg of each bar 14, 35 near one end, is a bracket 15, and secured to the same leg near the opposite end, is a lever 16. The brackets 15 are conveniently formed of a single L-shaped strip of metal pivoted, at 17, on a horizontal axis to the 40 depending leg of one of the bars 13. The levers 16 are preferably formed of two L-shaped strips, as clearly shown in Fig. 1, and are pivoted, at 18, upon horizontal pivots, to the depending leg of an adjacent bar 45 13, the pivots 18 alining with the pivots 17. Levers 16 are connected by a connecting link 19 so that they may be moved simultaneously and one side or member of the lever 16, secured to the rear bar 14, is extended 50 upwardly to form an operating handle 21. In order to stiffen the pivots 18, we arrange between said pivots and alongside the vertical leg of the adjacent angle iron 13, a

plate or bar 22, the levers 16 lying between the vertical leg of the adjacent bar 13 and 55 the bar 22. Secured between bar 22 and the vertical leg of the adjacent angle iron 13, is a segment 23 adapted to be traversed by the handle 21 and engaged by a suitable detent 24 in order to hold levers 16 at any desired angle relative to the bars 13 and thus determine the angle which the vertical legs of the transverse angle irons 14 may occupy relative to vertical planes.

Removably secured, by bolts 25, to the 60 substantially vertical legs of the cross irons 14, are scraper blades 26 and the line of connection between each scraper blade and its bar 14 is substantially midway between the edges of the blade so that said blades may 65 be readily reversed both facewise and endwise, thus bringing into action any one of the four edges of the blade. By this arrangement it is possible, when the scraping edge of any blade has become too dull, to 70 merely reverse the blade (either facewise or endwise) and thus bring into play a substantially sharp edge without the necessity of re-sharpening the blade. This is an important improvement as it saves very much 75 time and labor.

The inner bar 13 of each of the drags 10 and 11 is pivoted at 31 to a transverse draft bar 32 to which is secured a foot board 33, the ends of which are extended outward so 80 as to rest loosely upon the outer ends of the boards 13'. Several holes 31 are provided so that the two drags 10 and 11 may be adjusted bodily toward and from each other to 85 adapt the structure for operation on roads 90 of different widths. Secured to draft bar 32 are the rear ends of two draft chains 34, 34 which extend forwardly to a draft ring 35. The outer angle irons 13 of the two drags 10 and 11 have draft chains 36, 36 attached to 95 their forward ends and these draft chains at their forward ends are connected by a clevis 37 and pin 38 with the draft ring 35, the arrangement being such that the chains 36 may be readily lengthened or shortened 100 and thus permit the drags 10 and 11 to swing about the connections 31 as pivots and change the horizontal angle of the scraper blades relative to the roadway.

Attached to the rear end of each of the 105 inner bars 13 of drags 10 and 11 is a draft

chain 41 the rear end of each of which is attached to the forward end of an end bar 42 of the drag 12. The end bars 42 are conveniently made of angle iron having inwardly projecting legs and downwardly projecting vertical legs. Rigidly secured to the vertical legs of bars 42, by brackets 43, is a transverse bar 44. Similarly secured to bars 42, near their forward ends, by brackets 45, is a cross bar 46. The bars 44 and 46 may conveniently be made of angle iron having a rearwardly projecting leg and a downwardly projecting leg, the bar being set so that the downwardly projecting leg is also inclined rearwardly. Secured to each of the downwardly projecting legs of bars 44 and 46 are scraper blades 47 and 48, respectively, the lower edges of which are preferably shaped in such manner as to produce a proper crown 20 on the center of the road, as clearly indicated in Fig. 1.

In order to stiffen the rear drag 12 we secure, to the middles of the rearwardly projecting legs of bars 44 and 46, brackets 49 which have upwardly projecting legs to which are secured two parallel and closely adjacent bars 51, 51. The bars 51, 51 may be conveniently made of angle iron, and secured between them is an upwardly extending handle or bar 52 which is stiffened by a brace 53. Cross braces 54, 54, conveniently made of angle iron, extend between the bars 51 and the adjacent end bars 52, so as to further stiffen the rear drag structure.

The operation is as follows: Drags 10 and 11 are first adjusted toward or from each other by shifting the pivotal connections 31, to fit the road and are then given any desired horizontal angle, relative to the line of the roadway, by an adjustment of chains 36, whereupon the scraper blades 25 and 26 may be given any desired vertical angle relative to the surface of the roadway by an adjustment of handles 21. When properly adjusted, the drag is drawn along lengthwise of the roadway and the blades of drags 10 and 11 scrape the dirt toward the center of the road, conforming to the general crown of the road by reason of their interdependence. The rear drag serves to distribute and crown the dirt delivered to it by the blades of the forward drags 10 and 11. The operator stands upon the foot board 33 and, if he sees that it is desirable to vary the action of the rear drag, he can readily do so by grasping the upper end of arm 52. If he shoves backwardly on the upper end of this arm the forward scraper blade 48 will be lifted, the blade 47 serving as a pivot; if he pulls forwardly on arm 52 the rear scraper blade 47 will be lifted, the scraper 48 serving as a pivot, thus letting accumulated trash drop behind. By this action it is also possible to drop accumulated dirt at any point, as in a depression, etc.

It will be noticed that this drag has no side draft and that there is no tendency to sue from one side of a road to the other.

We claim as our invention:

1. In a road drag, the combination, of a draft bar, a pair of drags pivoted at their inner ends to said draft bar, scraper blades forming part of said drags, and draft chains connected with the draft bar and the outer ends of the drags. 75

2. In a road drag, the combination, of a draft bar, a pair of drags pivoted at their inner ends to said draft bar, scraper blades forming part of said drags and pivotally mounted about substantially horizontal axes, means for swinging the scraper blades upon their horizontal axes and holding them in various positions of adjustment, and draft chains connected with the draft bar and the outer ends of the drags. 80

3. In a road drag, the combination, of a draft bar, a pair of drags pivoted at their inner ends to said draft bar, scraper blades forming part of said drags, draft chains connected with the draft bar and the outer ends of the drags, and means for adjusting the length of the draft chains connected with the other ends of the drags whereby the horizontal angle of the drags relative to the line of the road may be adjusted. 85

4. In a road drag, the combination, of a draft bar, a pair of drags pivoted at their inner ends to said draft bar, scraper blades forming part of said drags and pivotally mounted about substantially horizontal axes, means for swinging the scraper blades upon their horizontal axes and holding them in various positions of adjustment, draft chains connected with the draft bar and the outer ends of the drags, and means for adjusting the length of the draft chains connected with the outer ends of the drags whereby the horizontal angle of the drags relative to the line of the road may be adjusted. 100

5. In a road drag, the combination, of a draft bar, a pair of drags pivoted at their inner ends to said draft bar, scraper blades forming part of said drags, draft chains connected with the draft bar and the outer ends of the drags, and a rear drag comprising transverse scraper blades and draft connections for said rear drag. 115

6. In a road drag, the combination, of a draft bar, a pair of drags pivoted at their inner ends to said draft bar, scraper blades forming part of said drags and pivotally mounted about substantially horizontal axes, means for swinging the scraper blades upon their horizontal axes and holding them in various positions of adjustment, draft chains connected with the draft bar and the outer ends of the drags, and a rear drag comprising transverse scraper blades and draft connections for said rear drag. 120

7. In a road drag, the combination, of a draft bar, a pair of drags pivoted at their inner ends to said draft bar, scraper blades forming part of said drags, draft chains connected with the draft bar and the outer ends of the drags, means for adjusting the length of the draft chains connected with the outer ends of the drags whereby the horizontal angle of the drags relative to the line of the road may be adjusted, and a rear drag comprising transverse scraper blades and draft connections for said rear drag.
8. In a road drag, the combination, of a draft bar, a pair of drags pivoted at their inner ends to said draft bar, scraper blades forming part of said drags and pivotally mounted about substantially horizontal axes, means for swinging the scraper blades upon their horizontal axes and holding them in various positions of adjustment, draft chains connected with the draft bar and the outer ends of the drags, means for adjusting the length of the draft chains connected with the outer ends of the drags whereby the horizontal angle of the drags relative to the line of the road may be adjusted, and a rear drag comprising transverse scraper blades and draft connections for said rear drag.
9. In a road drag the combination with a transverse draft bar, of a pair of drag structures, means for pivotally connecting each of said drag structures to said draft bar at any one of a series of positions whereby the drag structures may be bodily adjusted toward and from each other.
10. In a road drag the combination with a transverse draft bar, of a pair of drag structures, means for pivotally connecting each of said drag structures to said draft bar at any one of a series of positions whereby the drag structures may be adjusted toward and from each other, a draft ring, chains connecting said draft ring with the draft bar and chains connecting said draft

ring with the outer ends of the two drag structures, and means for varying the effective length of said last mentioned chains.

11. In a road drag the combination with a transverse draft bar, of a pair of drag structures, means for pivotally connecting each of said drag structures to said draft bar at any one of a series of positions whereby the drag structures may be bodily adjusted toward and from each other, a foot board carried by the draft bar and having transversely extending ends resting loosely upon the two drag structures.

12. In a road drag the combination with a transverse draft bar, of a pair of drag structures, means for pivotally connecting each of said drag structures to said draft bar at any one of a series of positions whereby the drag structures may be adjusted toward and from each other, a draft ring, chains connecting said draft ring with the draft bar and chains connecting said draft ring with the outer ends of the two drag structures, means for varying the effective length of said last mentioned chains, a foot board carried by the draft bar and having transversely extending ends resting loosely upon the two drag structures.

13. In a road drag, the combination of a draft bar, a pair of drag structures each pivotally connected to said drag bar at its inner end, means for holding each drag structure relative to the draft bar in different angular positions, and a foot board connected to the draft bar and having its outer ends resting loosely upon the drag structures.

In witness whereof, we, have hereunto set our hands and seals at Indianapolis, Indiana, this twenty-fifth day of October, A. D. one thousand nine hundred and nine.
